[57] CLAIM

The ornamental design for a submersible motor vehicle light, as shown and described.

DESCRIPTION

FIG. 1 is a top perspective view of a submersible motor vehicle light showing my new design;

FIG. 2 is a front view thereof;

FIG. 3 is a top view thereof;

FIG. 4 is a bottom view thereof;

FIG. 5 is a left-side view thereof, the opposite side view being a mirror image;

FIG. 6 is a rear view thereof; and,

FIG. 7 is an exploded view of FIG. 1, showing some elements of the design separated.
